AUTOMATIC STEADY REST FOR GRINDING MACHINES

George Crompton, Jr., Worcester, Mass., assignor to Norton Company, Worcester, Mass., a corporation of Massachusetts

Application November 19, 1936, Serial No. 111,570

7 Claims. (Cl. 51—238)

The invention relates to steadyrests for grinding machines.

One object of the invention is to provide a steadyrest system for a grinding machine facilitating the grinding of shafts, especially long shafts. Another object of the invention is to eliminate the necessity for continual adjustments of steadyrests in the grinding of long and especially flexible shafts. Another object of the invention is to permit the more accurate grinding of shafts and the like. Another object of the invention is to achieve extreme accuracy in the setting of a steadyrest, and more especially in the setting of a plurality of steadyrests. Another object of the invention is to move a plurality of steadyrests synchronously. Another object of the invention is to increase the production of shafts and the like which are ground. Another object of the invention is to increase production and accuracy in the grinding of any object held between centers and rotated. Another object of the invention is to provide a complete grinding machine of increased accuracy and with automatic operation of one or more steadyrests. Other objects will be in part obvious or in part pointed out hereinafter.

The invention accordingly consists in the features of construction, combinations of elements and arrangements of parts, as will be exemplified in the structure to be hereinafter described, and the scope of the application of which will be indicated in the following claims.

In the accompanying drawings in which is shown one of various possible embodiments of the mechanical features of this invention,

Figure 1 is a front elevation of a cylindrical grinding machine especially adapted for the grinding of long shafts and having apparatus according to the invention including four steadyrests;

Figure 2 is an enlarged transverse sectional view taken along the line 2—2 of Figure 1 through the work table and one of the steadyrests;

Figure 3 is a fragmentary view showing in front elevation the base for one of the steadyrest apparatus and in vertical section the slideway for the upper steadyrest element;

Figure 4 is a plan view of the upper steadyrest element;

Figure 5 is a fluid pressure diagram showing the connections for operating the steadyrests and also for operating the work table or carriage;

Figure 6 is a perspective view of one of the base castings of a steadyrest unit together with the two slideway castings attached in position.

Referring first to Figure 1, the invention may be embodied in or applied to a cylindrical grinding machine, sometimes referred to as a "plain" grinding machine, having a base casting 10 which, as shown in Figure 2, includes walls 11, 12 and 13 having flat and V ways 13 and 14, respectively, formed thereon for the support of a table or carriage 15 which, as shown in Figure 1, has fastened thereto the usual swivel table 16 having front and back ways 17, 18 by means of 19 which, referring again to Figure 1, a headstock 19 and a tailstock 20 are attached to the table 16 and therefore also the carriage 15. The headstock has associated therewith a stand 21 for the usual motor 22 having a pulley 23 driving a pulley 24 by means of belt 25. The shaft 26 upon which the pulley 24 is mounted is connected by gearing, not shown, in the head 19 to the usual work spindle, also not shown, which is accurately journaled in the head 19 and receives headstock 20 work center 27 adapted to fit in one of the center holes provided in the work piece, in this case a long shaft 30. Connected to the work spindle is the usual face plate 31 with radial slot 32 in which fits usual dog 33 fastened to the shaft 30. Tailstock 20 includes a hand wheel 35 for moving the usual tail center 36 horizontally, and suitable means, not shown, for clamping the tail center 36 in adjusted position. The apparatus described is not in itself novel and constitutes a preferred embodiment of means for holding and rotating the shaft 30 between centers and also supporting it for reciprocatory movement relative to a grinding wheel 40. The latter is fastened to a wheel spindle 41 journaled in a wheel head 42 which is mounted on slideways, not shown, normal to the slideways 13, 14, whereby the grinding wheel 40 may be caused to approach and recede from the shaft 30. The machine preferably includes cross feeding apparatus which may be of any desired type and is herein shown as including a shaft 45 which may be the driving screw shaft and which is operated by a ratchet 46 and pawl 47 together with suitable micrometer control indicated at 50 and automatic actuating apparatus 51 for the pawl 47 of a type now well known and which is moved by the main reversing lever 52 which controls the travel of the carriage 15. This mechanism is not herein described in detail as any equivalent or substitute therefor may be provided, and the cross feed may be hydraulic or mechanical or of any other desired type, many now being well known in the art.

Referring to Figure 1 in connection with Figure 5, I may provide any suitable apparatus for

reciprocating the carriage 15. Relative reciprocation of the work piece and grinding wheel 40 is desired so far as certain features of the invention are concerned, and although it is now preferred to reciprocate the work piece, means for reciprocating the grinding wheel may be substituted therefor. Referring now to Figure 5, I have therein illustrated a pair of brackets 56, 56 depending from the carriage 15 extending between which is a long piston rod 57 having a piston 58 fastened thereto and located in a closed cylinder 59. Pipes 60 and 61 are connected to opposite ends of the cylinder 59 and lead from opposite sides of a main control valve casing 62. The bottom of the valve casing 62 is connected to a pump 63 while the top thereof is connected to an exhaust pipe 64. Pump 63 draws oil or other suitable fluid from a tank 65 while the pipe 64 exhausts into the tank 65 by way of a throttle valve 66. A movable valve member 67 in the casing 62 is connected to the pivot shaft 68 of the reversing valve member 52. A suitable snap-over or load and fire device, not shown, is provided to achieve a reversal in direction of travel of the carriage 15 as distinguished from a mere stop. The carriage 15, as shown in Figures 1 and 2, has a "T" slot 70 in which are adjustably fastened striking dogs 71, 72 to engage the reversing lever 52, thus to reverse the direction of travel of the carriage 15. The foregoing brief description of a typical hydraulically actuated plain cylindrical grinding machine is given not by way of limitation but in order more readily to illustrate the preferred application of the invention.

Referring now to Figure 1, for the grinding of a long shaft 30 it has been customary to provide steadyrests. If a shaft were a rigid body, steadyrests might be dispensed with but even a steel shaft of the relative dimensions shown is a flexible body when dealing in measurements of a thousandth of an inch and less. In fact, even very much shorter shafts may require one or more steady rests for precision grinding to within small limits owing to the inevitable spring which develops in the shaft or rod as it is being ground.

In the illustrative embodiment of the invention, I show four steadyrest mechanisms 75 but more or less may be provided, depending upon the particular requirements. Each of these steadyrest mechanisms 75 may be and preferably is a duplicate of all the others.

Referring now to Figure 2, each steadyrest has a base casting 76 having an overhanging portion 77 which fits on the ways 17 and may be clamped thereto by means of L head bolts 78 which engage dovetailed lip portion 79 of the table 16 and which bolts may be tightened by nuts 80 shown in Figures 2 and 3. Casting 76 also has a foot portion 81 which rests on table 16. The casting 76 likewise includes parallel side portions 82 between which extends a block 83 which is bored out to form a cylindrical bore 84 in which fits a piston 85 backed up by a spring 86. Piston 85 has a piston rod 87 extending through a cylinder head 88 which may fit in screw threaded engagement with the block 83.

Referring now to Figure 5, a pipe 90 is connected to the pump 63 and is also connected to a horizontal pipe 91 which extends between stationary portions 92, 93 of the machine base. The pipe 91 does not move, but slidably mounted on it is an oversized cylinder 94 having cylinder heads 96 bored to receive the pipe 91 with a fluid

tight sliding fit. Approximately in the center of the pipe 91 is an orifice 97 so that the cylinder 94 is filled with fluid under pressure at all times when the pump 63 is running. Considering now Figures 2 and 5, the cylinder 94 is attached to the under side of the carriage 15 and moves with it. A pipe 98 extends upwardly from the cylinder 94 to a long pipe 100 which is parallel to the cylinder 94 and in fluid connection with it. Connected to the pipe 100 are a plurality of valve members 101 individually controlled, as shown in Figures 1 and 2, by hand wheels 102 located on the front of the machine. On the upper part of each valve 101 is a fitting 103 which is connected to a flexible hose or pipe 104, there being four of these hoses in the illustrative embodiment of the invention as well as four of the valves 101 where four steady rest mechanisms 75 are provided. Each hose or flexible pipe 104 is connected to a nipple 105 located in the side of the block 83 and communicating with the inside of the bore 84 thereof.

Comparing now Figures 2 and 6, I provide a slideway casting 110 for each steadyrest mechanism which may be U shaped in cross section, as shown, and it is preferably carefully ground to provide accurate, smooth slideway surfaces for a steadyrest element 111 which is shown out of the machine in plan view in Figure 4. This slideway member 110 has flanges 112 through which extend suitable bolts 113 by means of which it is fastened to the sides 82 of the casting 76 which it bridges. In the bottom of the slideway 110 is an opening 115 for an actuating lever 116 pivoted on a shaft 117 which extends between the side portions 82. On the upper end of the lever 116 is a roller 118 which engages the head of the bolt 119 which projects into a cutout portion 120 of the steadyrest member 111. The bolt 119 may be suitably tightened in position by means of a nut 121.

I provide further a similar slideway member 110a in which is located a steadyrest member 111a having a cut-out portion 120a into which projects a bolt 119a the head of which is engaged by a roller 118a on the end of a lever 116a pivoted on a shaft 117a extending between the side portions 82, the slideway 110a being fastened to the base 76 in a manner similar to that described and fully shown for the slide member 110. The other ends of the levers 116 and 116a have ball portions 125 and 125a located in a collar portion 126 formed on the piston rod 87 for the piston 85.

Referring again to Figure 5, I provide a two-way valve 130 in the line 90 adapted in the position shown to connect the two sections of the pipe 90 and in another position to disconnect the two sections of the pipe 90 and connect the left-hand section thereof to a discharge pipe 131 which empties into the reservoir 65. The movable member of the valve 130 may be operated by a lever 132 which, as shown in Figure 1, may be located on the front of the machine and which has two positions, shown in full and dotted lines, respectively, the former representing the position in which the two sections of the pipe 90 are connected together, and the latter representing the position in which the left-hand section of the pipe 90 is connected to the exhaust pipe 131.

All of the steadyrests may be operated in unison by means of the control lever 132. Any one of the steadyrests, however, may be put out of action by its individual control valve 102. Each cylinder bore 84 has a bleed hole 135 in the bot-

tom thereof through which any oil leaking past the piston 85 may discharge. This oil may collect in a groove 136 running lengthwise of the table 18 in the inside thereof. A hole 137 extends through the table 18 and is aligned with a countersunk portion 138 communicating with a bore 139 in the carriage 15. A cross bore 140 leads the oil thus discharged to the carriage ways 13 and 14. In this manner blocking of the several piston and cylinder actuating mechanisms by entrapped oil is prevented and the oil is usefully disposed of.

On the front of the slideway 110 and on the bottom of the slideway 110a are end plates 145 and 145a, respectively. Extending through these end plates are bolts 146 and 146a respectively on which are located springs 147 and 147a respectively. These springs insure the retraction of steadyrest elements 111 and 111a whenever the pistons 85 move upwardly in the cylindrical bores 84 of the blocks 83.

It will be observed from Figure 2 that the levers 116 and 116a are duplicates of each other. Furthermore, the axis of the cylindrical bore 84 and of the piston 85 intersects the axis of the work piece 30 and lies at an angle of 45° to the horizontal plane of the work piece axis and also 45° to the vertical plane of the work piece axis. Furthermore, the steadyrest element 111 is mounted to move horizontally and the steadyrest element 111a is mounted to move vertically. The steadyrest element 111 has two steadyrest shoes 150 and 151 which have plane surfaces for tangential contact with the work piece 30, the plane of the surface of the shoe 150 being parallel to the axis of the piston 85 and inclined at 45° to the horizontal. The contacting tangential plane of the shoe 151 is inclined 45° to the horizontal and is normal to the axis of the piston 85 and it follows that it is, therefore, normal or perpendicular to the contacting surface of the shoe 150. The steadyrest element 111a has but a single contacting shoe 152, the contacting surface of which is parallel to the axis of the piston 85 and also parallel to the surface of the shoe 150. While some of these relationships may be changed, it will be seen that this represents a balanced construction. Movement of a thousandth of an inch (or any other distance, for that matter) of the element 111 is accompanied by exactly equal movement of the element 111a.

As a result of this geometrical arrangement, the work piece 30 cannot be pushed out of its normal position coaxial with the centers 27, 36 of the grinding machine. Stating this in another way, the work piece 30 is held in a given or constant position as the steadyrests advance. Nevertheless, each steadyrest may exert any pressure on the work piece and may advance automatically in response to the hydraulic pressure of the system described. This hydraulic pressure represents a force rather than a positive movement by reason of the provision of a pressure relief valve 155 in the pipe line 90, as shown in Figure 5.

It follows from the foregoing that, in case a plurality of steadyrest mechanisms grip the work piece, it will be truly centered thereby and the machine work centers 27 and 36 are relieved of the load of the work piece. In fact, once the work piece is centered by a plurality of steadyrests 75 as described, the center 36 may be backed off altogether so that it no longer centers the work piece (wherefor the other center 27 will no longer center the work piece), provided any suitable

means is provided to prevent endwise movement of the shaft 30. In the operation of the machine, the centers 27 and 36 will preferably be kept in their usual positions relative to the work piece 30 or merely backed off a few thousandths of an inch in order to prevent endwise movement of the shaft 30. Nevertheless distinct advantages are achieved by providing a plurality of steadyrest mechanisms which automatically and accurately locate the work piece in so much as accuracy of 10 location of the center holes in the work piece is no longer a matter of such importance. In other words, the work piece may be ground to concentricity with its previously turned cylindrical surface rather than to concentricity with the end 15 center holes.

The automatic operation and centering of the steadyrest mechanisms renders it possible to grind a long shaft like the shaft 30 with no interruptions for adjustment of steadyrests and by 20 a continuous grinding operation and with greater accuracy than has heretofore been possible. The uncertainties of operator control are greatly reduced by this automatic centering mechanism 25 described.

The relationship of the surfaces of the shoes 150, 151 and 152 is such as to make a three-sided box for the work piece, the grinding wheel 40 being at one of the other sides so that the work piece cannot move therefrom but is locked in position. Furthermore, as the shoes 150 and 152 face each other, steadyrest elements cannot advance beyond the point where they are in tangency with the work piece as otherwise they would have to compress the shaft 30 which is virtually impossible, that is to any appreciable or significant extent with the pressures involved. The several shoes 150, 151 and 152 may be made of very hard material, for example they may be removable plates of pressed boron carbide or other similar substance or, on the other hand, they may be simply case hardened surfaces. It will be seen that the location of the various steadyrest mechanisms 75 may be varied on the machine within reasonable limits by reason of the flexibility of 45 the pipes 104 and also one or more of the complete mechanisms may be readily removed from the machine altogether. Vital parts of the mechanisms including the slideways 110 and steadyrest elements 111 may be readily removed and replaced if they lose their accuracy on account of wear. If desired, I may provide removable cover plates 156 for the slideway members 110 and similar cover plates, not shown, for the slideway members 110a to keep dirt out of the apparatus. 50 55

A feature of importance is that in all positions of the actuator 85, the steadyrest surfaces are equi-distant from the axis of the work piece. The axis of the work piece is the axis of the machine centers. However, the steadyrest surfaces 60 themselves govern the position of the geometrical axis of the work piece by moving so that they are at all times equi-distant from a given line and cause this geometrical axis to be the axis of rotation, a condition distinctly to be desired in grinding. Measurements from the steadyrest surfaces to the axis of the work piece are made normal to the planes of the surfaces, so that the measuring lines are the radii of the work piece. 65

It happens to be the case in the illustrative 70 embodiment of the invention that the elements 111 and 111a move equal increments. This is because the dihedral angle of the surface 150 to the horizontal plane of the work piece axis is the same as that of the dihedral angle of the plane 75

of the rest 152 to the vertical plane of the work piece axis, viz. in both cases 45°. It is further because the dihedral angle of the plane of the rest 151 to the horizontal plane of the work piece axis is the same as that of the rest surface 152 to the vertical plane of the work piece axis, viz. 45°. It will be remembered that the element 111 moves in the horizontal plane of the work piece axis and the element 111a moves in the vertical plane of the work piece axis. However, the plane of the rest surface 152 might be at a dihedral angle other than 45° to the vertical plane of the work piece axis, in which case the lengths of the levers 116 and 116a would be changed to cause the elements 111 and 111a to move at different increments. With the plane of approach of each steady rest element known and the angles of such planes to the planes of the steadyrest surfaces known, the proportionate lengths of the several lever arms 116 and 116a can be readily determined geometrically. I prefer, however, to so locate the various surfaces, as in the illustrative embodiment of the invention, that the steadyrest elements are prevented from moving beyond that point where they center the work piece in the desired position and this may be achieved using three steadyrest surfaces as shown in the same general relationship, or it may be otherwise achieved.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:—

1. A steadyrest mechanism for grinding machines and the like comprising a steadyrest element having two surfaces in the form of a V, a second steadyrest element having a single surface, an actuator for both elements, and connections whereby all three surfaces remain equi-distant from a given line in all positions of the actuator, measurements being made normal to said surfaces from the said line.
2. In a grinding machine, a plurality of steadyrests each having two movable steadyrest elements, fluid actuating pressure mechanism for simultaneously urging all of the several elements of all of the steadyrests against a work piece, and positive connections between the fluid

pressure actuating mechanism and the steadyrest elements positively to move each steadyrest element in definite relation to the other steadyrest element of such steadyrest.

3. A steadyrest mechanism comprising an actuator, fluid pressure means for moving the actuator, two steadyrest elements, two slideways for mounting said steadyrest elements for movement located in such positions that the line of advance of the actuator bears the same angular relation to each of the slideways, and actuating connections between the steadyrest elements and the actuator of similar characteristics.

4. In a grinding machine, a movable table or carriage, a steadyrest on said carriage, fluid pressure actuating mechanism on said carriage for said steadyrest, a fluid pressure pump located in the stationary part of the machine, and fluid connections between the pump and the fluid pressure actuator including a sliding piston and cylinder connection.

5. A steadyrest mechanism comprising two steadyrest elements and having three steadyrest surfaces, there being two surfaces on one steadyrest in the form of a V, the dihedral angle of such V being twice that of the angle between the steadyrest surface on the other steadyrest element and the line of its advance, and positive connections between said steadyrest elements to cause them to move by equal increments at all times.

6. In a grinding machine, a base, a carriage mounted for movement on said base, a plurality of fluid pressure actuators on said carriage, fluid pressure means constituting a source of fluid under pressure in said base, fluid pressure connections between said fluid pressure means and each of said actuators, a plurality of steady rest elements having steady rest surfaces for each actuator, and mechanical connections between each fluid pressure actuator and its steady rest elements whereby all steady rest surfaces of said elements move in loci equidistant from a given line in all positions of such actuator.

7. In a grinding machine, a plurality of fluid pressure actuators, fluid pressure means constituting a source of fluid under pressure, fluid pressure connections between said fluid pressure means and each of said actuators, a plurality of steady rest elements having steady rest surfaces for each actuator, and mechanical connections between each fluid pressure actuator and its steady rest elements whereby all steady rest surfaces of said elements move in loci equidistant from a given line in all positions of such actuator.

GEORGE CROMPTON, JR.
